UNITED STATES PATENT OFFICE.

CORNELIUS EVAN JOHNSON, OF GRAND RAPIDS, MICHIGAN, ASSIGNOR TO THE PROUD-FIT LOOSE LEAF COMPANY, OF GRAND RAPIDS, MICHIGAN, A CORPORATION OF MICHIGAN.

LOOSE-LEAF DEVICE.

1,272,963.

Specification of Letters Patent. Patented July 16, 1918.

Application filed February 8, 1917. Serial No. 147,372.

To all whom it may concern:

Be it known that I, CORNELIUS EVAN JOHNSON, a citizen of the United States, residing at Grand Rapids, in the county of 5 Kent and State of Michigan, have invented new and useful Improvements in Loose-Leaf Devices, of which the following is a specification.

The present invention relates to loose-leaf 10 devices, and its object is to provide a device of that character in which the leaf members may be very securely held and into which they may be readily inserted and from which they may be readily removed; and further to 15 provide in such a device leaf members with pockets, of improved and economical construction.

These objects are attained by, and the invention finds preferable embodiment in, the 20 device hereinafter described and illustrated by the accompanying drawings, in which:—

Figure 1 is a view in perspective of a loose-leaf device;

Fig. 2 is an end view of the back member 25 and of the leaf members thereof;

Fig. 3 is a view in perspective of the back member;

Fig. 4 is a like view of a removable plate;

Fig. 5 is a sectional view of a pair of leaf 30 members, each of which has a pocket, and taken on a plane corresponding to line 5—5 of Fig. 1; and,

Fig. 6 is a like view of a part of one of said leaf members taken on a plane corresponding to line 6—6 of Fig. 1.

In the embodiment of the invention chosen for illustration by the drawings and for detailed description in the body of this specification, the device is shown as a book having 40 leaf-members with pockets adapted to contain phonograph records. A back member 1 has longitudinally-extending grooves 2, the sides of each such groove in the construction shown converging toward its mouth, so that 45 the bottom portion of the groove is wider in cross section than its mouth. Each leaf member 3 has a bight portion 4 adapted to be inserted into said groove and to be held therein against lateral removal by a rod 5 50 in the bight of the bight portion, the diameter of the rod together with the thickness of the bight portion being in said construction greater than the cross sectional dimension of the groove at its mouth.

55 In the structure illustrated, two leaf mem-

bers have a common bight portion so that both said members are held in one groove and by one rod. The leaf members together with the rods laid in the bights of the bight portions are inserted into the grooves in the 60 endwise direction of the rods, and when so inserted are held in the grooves by plates 6, at least one of which is removable, secured to the end of the back member as by the screw 7, and extending across the ends of the 65 grooves, thus covering the edges of the bight portions and the ends of the rods. When the plate is removed, the rods and bight portions may be slid out. The device is shown provided with covers 8.

70 The leaf members are formed with pockets 9 therein having closed edges 10, 11, and bottoms 12 and adapted to contain phonograph records, the construction as shown being as follows: A sheet, as of paper, is folded 75 to form one edge 10 of the pocket at the free end of the leaf member, and the sheet's edges at the opposite side are riveted at 13 to the bight portion or binding-edge portion 4 between them (Fig. 5). The lower end 15 of 80 one fold 14 of the sheet is turned over and secured as by glue to the other fold 16 of the sheet to form the closed bottom of the pocket (Fig. 6).

85 The invention being intended to be defined solely by the claims, is not to be limited to or by details of construction shown or described.

What is claimed is:

1. In a device of the character described; 90 a back member having longitudinally-extending grooves; leaf members having pockets adapted to contain phonograph records and having bight portions adapted to be inserted into the grooves; and releasable means for retaining the bight portions in the grooves.

2. In a device of the character described; 100 a back member having longitudinally-extending grooves with sides converging toward the mouths of the grooves; leaf members having pockets adapted to contain phonograph records and having bight portions adapted to be inserted into the grooves; and releasable means for retaining the bight portions in the grooves.

3. In a device of the character described; 105 a back member having longitudinally-extending grooves with sides converging toward the mouths of the grooves; leaf mem-

bers having pockets adapted to contain photograph records and having bight portions adapted to be inserted into the grooves; rods in the bights of said portions and adapted to releasably hold the same in the grooves against lateral removal.

4. In a device of the character described, a back member having longitudinally-extending grooves with sides converging toward the mouths of the grooves; leaf members having bight portions adapted to be inserted into the grooves; rods in the bights of said portions and adapted to releasably hold the same in the grooves against lateral removal; and releasable means for holding the bight portions and the rods against longitudinal removal.

5. In a device of the character described; a back member having longitudinally-extending grooves with sides converging toward the mouths of the grooves; leaf members having bight portions adapted to be inserted into the grooves; rods in the bights of said portions and adapted to releasably hold the same in the grooves against lateral removal; and a removable plate at the end of the back member extending across the open ends of the grooves and adapted to hold the

bight portions and the rods against longitudinal removal.

6. In a device of the character described; a leaf member having a binding-edge portion and a pocket made by folding a sheet to form an edge of the pocket at the free end of said member opposite the binding-edge portion and by riveting the edge portions of the sheet to the binding-edge portion between them.

7. In a device of the character described; a leaf member having a binding-edge portion and a pocket made by folding a sheet to form an edge of the pocket at the free end of said member opposite the binding-edge portion and by riveting the edge portions of the sheet to the binding-edge portion between them, and by folding the bottom portion of one fold of the sheet and securing the same to the other fold of the sheet.

In testimony whereof I have hereunto set my hand, in presence of two subscribing witnesses, at Grand Rapids, Michigan, this 5th day of February, A. D. 1917.

CORNELIUS EVAN JOHNSON.
